UNITED STATES PATENT OFFICE.

WILLIAM JOSLIN, OF CLEVELAND, OHIO.

IMPROVED CLOTHES-WRINGING MACHINE.

Specification forming part of Letters Patent No. 36,218, dated August 19, 1862.

To all whom it may concern:

Be it known that I, WILLIAM JOSLIN, of Cleveland, in the county of Cuyahoga and State of Ohio, have invented a new and useful Improvement in Clothes-Wringers; and I do hereby declare that the following is a full and exact description thereof, reference being had to the accompanying drawings, and to the letters of reference marked thereon, making part of this specification.

The nature of my invention consists in a simple arrangement of levers and springs for pressing the rubber rollers together, and in the employment of a double right and left hand circular inclined plane or section of a double-thread screw for holding the machine upon the tub.

Figure 1 is a front elevation of my improved wringing-machine. Fig. 2 is an inside end elevation. Fig. 3 is a top view of the same. Fig. 4 is a view edgewise of one of the double circular inclined planes. The red lines represent a face view.

A and A² in Fig. 1 are the ends or standards, each having jaws, between which the tub passes when fastened to it, as shown by K and K² in Fig. 2.

B and B² are the rubber rollers, between which the clothes pass in the operation of wringing.

C and C² are crooked or somewhat S-shaped levers, being fastened to the standards by means of pins in the ears d and d² on the outside of the standards A and A² and working parallel with the rollers B and B².

D and D² are bars or rods which hold the ends or standards A and A² firmly in their position.

E and E² are caps or boxes (shown by red lines) resting upon the tops of the axis of the upper roller, B. The tops of the caps or boxes upon which the levers C and C² rest are rounded, so that the levers may work or rise and fall with ease. The bottom of the cap E and the bottom of the cap E² are made concave, to fit the pins or axis of the upper roller, B, as shown at E² in Fig. 2. The caps E and E² work in vertical slots, as shown at E and E² in the top view of Fig. 3.

F and F² in Fig. 1 are loop-form rubber springs. The loop spring F is passed under the lever C, toward the cap E, and over the top of the small end of the lever C². The spring F is adjusted to make more or less pressure on

the roller B by moving it in the notches made in the bottom of the lever C and notches made in the top of the lever C². The spring F² is attached to the opposite ends of the levers C and C² and adjusted by the notches on the bottom of the lever C² and the notches on the top of lever C in the same manner as the spring F. Metallic springs may be applied and adjusted in the same manner as the rubber springs. By moving the springs F and F² toward the center of the levers C and C² the pressure is diminished, so that any desired pressure may be produced with very little trouble. By this arrangement of levers and springs the pressure is nearly the same with a thick or thin article, because the springs move up and down with the levers, and the pressure does not increase as fast as if one end of the springs were fastened to some stationary part of the machine. The difference of pressure upon a thick or thin article seems to be the difference between the spaces moved through by the notches on the bottom of the levers C and C² and the notches on the top of the levers C and C². If the springs F and F² are placed in the notches indicated by the red lines V and V², when the notches in the bottom of the levers C and C² move up on the curved lines X and X² to the points O and O² the notches on the top of the levers C and C² will have moved on the curved lines W and W² to the points S and S², thereby causing the springs V and V² to expand one-half less than they would have expanded if the lower end of the springs were attached to a stationary part of the machine. It will now be seen that the expansion or pull of the spring V is up on the lever C and down on the lever C², and the expansion or pull of the spring V² is up on the lever C² and down on the lever C, thereby causing nearly the same pressure on a thick or thin article when passed between the rollers B and B², which is a result in mechanics very much desired by spring and lever pressure. I have said the difference of pressure upon a thick or thin article seems to be the difference between the spaces moved through by the notches on the levers. This would be true if the springs did not pull up on the levers; but the springs, pulling up on the levers as well as down, produce nearly an equal pressure, as above stated, the thickest article receiving the greatest pressure.

K and K² in Fig. 2 are the jaws which hold

the machine upon the tub. a and a' and b and b' are the four sides of a toothed mortise in the jaw K' , in which the double right-hand circular incline planes move. G' is the double right-hand circular incline planes or section of a double thread-screw with a pin or shaft passing through the center, with the handle H' at right angles with the shaft. The shaft passes through the center of sides b and b' of the mortise. The incline planes are fastened to the shaft by means of a small pin. a in the top of the mortise and a' in the bottom of the mortise are cogs or teeth against which the circular incline planes act. When the handles H and H' are turned toward the center of the machine, as in Figs. 1 and 3, the inclines act against the outside or front of the cogs a and a' in Fig. 2, thereby causing the center of the inclines to move against the front side, b' , of the mortise, carrying the shaft and handle H' with it, thus holding the handles H and H' in the position shown in Figs. 1 and 3. The double circular incline planes G in Figs. 1 and 3 are left-handed, and the double circular incline planes G' in Figs. 1 and 3 are right-handed. When the handles H and H' are moved out, as indicated by the arrows in Fig. 1, the inclines come in contact with the insides or backs of the cogs a and a' and cause the circular inclines, shafts, and handles to move in toward the jaw K , as shown by the red lines in Figs. 2 and 3, thereby holding the machine to the tub by pressing the shafts or pins against it by means of the double right and left hand circular incline planes G and G' , cogs a and a' , and handles H and H' in Figs. 1, 2, and 3.

The perfection and simplicity of this arrangement will be readily seen. When the machine is fast on the tub, the handles are in the position indicated by the red lines H and H' in Figs. 1, 2, and 3. When the machine is taken off from the tub, the handles are turned up and in toward the center H and H' , Fig. 1, and there remain until placed upon the tub again, thus keeping the pins or shafts out of the way when the machine is put again on the tub. The machine is fastened to any-sized tub with less than a revolution of the right and left hand circular inclines, thereby bringing the handles H and H' on the outside of the machine, out of the way of the clothing as it passes from the rollers to the basket after being wrung. The same effect may be produced by one circular incline on each shaft, but not with the perfection of the double circular incline planes. The left-hand circular incline planes, G , work in a mortise, the same as that described in Fig. 2.

After thus describing my invention, what I desire to secure by Letters Patent is—

1. The springs F and F' , acting upon the levers C and C' , as above described.
2. The right and left hand circular incline planes G and G' , the toothed mortise a and a' b and b' , and the shafts and handles H and H' , the parts being constructed and operated substantially in the manner and for the purpose set forth.

WM. JOSLIN.
